DRY SHAVER

Emile Gagnan, Montreal, Quebec, Canada

Application February 2, 1948, Serial No. 5,800
In France February 4, 1947

6 Claims. (Cl. 30—43)

1

The present invention relates to shaving devices and, more particularly, such a device of the so-called "dry shaven" type adapted to be actuated solely by its displacement over the skin to be shaved.

In the known types of dry shavers the hair cutting device consists of a thin, apertured, grid behind which a cutting element is oscillated or rotated to shear the hair. For proper operation, however, the contact between the grid and cutting element must be perfect, whereby the construction of the parts must be effectuated within narrow limits of precision and the size thereof limited as much as possible. Consequently, such shavers are generally satisfactory insofar as the cutting element is rapidly actuated by electrical and the like means.

The present invention has been conceived to avoid the disadvantages noted above and, accordingly, its design is such that no particular precision in the constituent parts is required, that the surface of the grid can be such as to enable contacting a large area of the skin, and that a simple manual movement is all that is essential for good results although, naturally, mechanical operation is not thereby excluded.

Characteristics of such a grid are:

1. It has no intrinsic rigidity, being a simple normally plane perforated plate of flexible and thin metal;
2. Inherently, it opposes no resistance to skin pressure.

From the foregoing, therefore, the objects of the invention may be stated as follows:

The main object of the invention resides in the provision of a motorless, efficient dry-shaver of improved construction.

Another object is the provision of such a shaver which has a long useful life. A further object contemplates a dry shaver which can be taken apart easily and rapidly for cleaning and whetting.

Still another object concerns a dry shaver of the character described which is easily operated with a minimum of effort.

A still further object envisages a dry shaver of simple, rugged construction and relatively inexpensive.

Other objects and advantages of the invention will become apparent, or be further pointed out, during the description to follow.

As examples, and for purposes of illustration only, three forms of the invention are shown in the annexed drawing, wherein:

Figure 1 is a perspective view of a user operating a shaver according to the invention;

2

Figure 2 is a perspective view of the shaver in operative position;

Figure 3 is another perspective view of the constituent elements of the shaver in disassembled position;

Figure 4 is a longitudinal vertical section taken centrally through the assembled shaver;

Figure 5 is a transverse vertical section taken centrally through the shaver;

Figure 6 is a view similar to Fig. 5 but showing a slightly modified form of the invention;

Figure 7 is yet a longitudinal section corresponding to Fig. 4 but of still another modification, and

Figure 8 is a transverse section taken at right angles to that of Fig. 7.

Referring to the drawing, wherein similar reference characters represent corresponding parts throughout, the reference letter S indicates generally in Figs. 1 and 2, the completely assembled shaver of the invention, especially the preferred form illustrated in Figs. 1 to 5 inclusive. According to all forms, however, a casing is provided with an aperture closed by a grid and a carriage movable inside the casing, and operated by a slider disposed outside the casing, said carriage carrying a plurality of cutting blades reciprocated against the inside face of the grid.

Consequently, in the original form of the invention depicted in Figs. 7-8, the casing 10 of quadrangular formation has an aperture 11 formed in the bottom or floor thereof and outwardly directed flanges 12 at the upper edge of its lateral walls (see Fig. 8).

A thin, flexible and perforated plate 13 closes the aperture 11, by resting on the edges 14 thereof, and constitutes the grid already mentioned. It must be noted that this grid has its edges free so as to bear against cutting blades to be described presently, said grid resting on the inner flanges constituted by the edges defining the aperture of the casing.

Said blades 15 are secured to the carriage block 16, against inclined milled faces thereof, so that said blades contact the grid at the proper angle best calculated for good results. The securing means for the blades may be the rivets 17, or the like.

The carriage is constituted by a pair of cover plates 18-19 adapted to fit one within the other and both formed with an inward flange 20 at the edge of downwardly-depending side walls. As shown to advantage in Figs. 7-8, the said flanges 20 are spaced so as to form slides in which 55 the flanges 12 of the casing 10 are engageable: thus, the covers 18-19 form together a sliding

carriage to which the block 16 is secured, as by the screws 21. Consequently, relative movement, between the casing and carriage, will reciprocate the blades over the grid and cause the shearing of hair protruding through the openings of the grid: the proper operating position is illustrated in Fig. 1, wherein the casing is held frictionally against the skin and the carriage grasped for reciprocatory movement.

An improved modification is shown in Figs. 2 to 5 inclusive, said modification embodying an easily demountable casing and a pull-back spring. The said casing is formed of a rectangular shallow base B, the bottom 25 of which is provided with a rectangular aperture 26; the side walls 27 of the base are apertured at 28, for allowing passage of the cut hair, while one end wall is formed with an inward projection 29.

A cover C is adapted to be removably engaged with the base, to form the casing C, said cover being also of rectangular formation and adapted to fit within the walls of the base. Said cover is comprised of the top plate 30 having depending side and end walls, as shown in Fig. 3. For holding the cover in proper position in the base, so that top 30 and bottom 25 are maintained in parallel relation, lugs 31 are struck outwardly from the walls of the cover to contact the upper edge of the bottom walls said lugs limiting penetration of the cover so that a space is left therebetween and the bottom 25. This space is intended to leave the grid G quite free over the aperture 26. The cover is frictionally held by the projection 29 entering a corresponding depression 32 on one end wall thereof. (Fig. 4.)

The blade-supporting carriage is in this modification, formed of a back-plate 35 the ends of which are bent right-angularly and to which the blade support is secured; this support consists of a cup-like member 36 the floor of which is pressed angularly into a series of inclined faces, a cutting blade 37 being riveted, or otherwise secured, to each alternate face 38.

The carriage is mounted on the cover by means of rivets 40 extending through slots 41 thereof and securing together the back plate 35 and a flanged slider 50 disposed above and straddling the cover C, the flanges 42 thereof acting as grasping cheeks for holding and operating the shaver. Spacing washers 45 around the rivets insure easy action by preventing pinching or binding of the cover between slider and carriage. As shown in Fig. 4, a return spring 46, tensioned between carriage and one end of the cover, acts at all times to urge the carriage in one end-position of rest.

The third modification shown in transverse section only in Fig. 6 is very substantially the same as that just described: the sole exception is in the mounting of the cover C which is movable and to which the blade-supporting carriage back plate 35 is directly riveted at 51. The cover C, herein represented by the numeral 52, is frictionally and removably engaged to a slider 53 having its side walls bent at 54 to form slides in which the flange 55 of the base B are engageable. Thus, the cover C and the attached carriage can be caused to reciprocate, relative to the fixed grid, through the intermediary of the slider 53.

From the foregoing description the construction and operation of the shaver should be evident: a thin, flexible, perforated grid is held in flat position over an apertured base which is stationary with respect to a set of angular blades, or knives, secured to a carriage reciprocated back

and forth. Consequently, the grid is supported by the knives only, when skin pressure is applied to the grid, and whatever pileous growth occurs thereon is severed by the shearing action of the knives on the grid.

This characteristic is found in all forms of the invention, although variations therebetween involve the mounting of the knives carriage and the demountability of the cover for gaining access to the grid and the knives, for whetting and cleaning purposes.

The advantages of the shaver according to the invention should be evident: due to the large surface of the plane grid and its flexibility, a relatively large area of skin can be covered at once and the contour thereof better contacted. Furthermore, the loose placement of said grid requires little accuracy in the shaver assembly, the only requirement being that the knives contact the grid.

Due to its relatively large surface said grid is less subject to wear and, in any case, it can be reversed and used on both sides, as well as turned end to end so that its normal life, compared to the usual grids used in one position only, is increased threefold.

Again, the knife assembly being easily accessible, it is a simple matter to whet the cutting edges on a flat stone and strop the same on a leather: in other words, disassembly being such an easy matter the keeping of the shaver in perfect operating condition can be attended to by any one. Finally, the grid can be replaced at little cost for reasons obvious from the above.

It must be understood that various changes as to the shape, size and arrangement of parts can be resorted to without departing from the spirit of the invention; for example, the shaver shown embodies a plane grid and a linearly reciprocable carriage; but it is clear that the shaver as a whole could be curved somewhat without altering the relation of the parts described and illustrated and still remain within the scope of the subjoined claims.

Having thus described my invention, I claim:

1. In a dry shaver, a casing having an aperture in the bottom thereof, a foraminous grid covering said aperture, a cover slidably mounted on the edges of the casing to reciprocate longitudinally with respect thereto, a carriage member secured inside said cover, and a plurality of inclined knives mounted on the carriage and movable therewith in contact with the inside face of the grid.

2. A dry shaver comprising a substantially quadrangular casing base having an aperture in the bottom thereof, a thin flexible foraminous plate freely resting on the edges of said aperture, a slotted cover removably mounted over the base, a slideable plate mounted over the cover, a carriage secured to the plate by means extending through the slots of the cover, and a plurality of inclined knives mounted under the cover and adapted to rest on the inside face of the grid and be reciprocated thereover in accordance with movements imparted to the slider.

3. A shaver of the dry motorless type, comprising a rectangular frame having an aperture, a flat flexible foraminous grid freely resting on the edges of the aperture, a slideable plate slidably connected with the edges of the frame, a cover frictionally and removably associated with the slideable plate, a carriage secured inside the cover, and cutting blades angularly attached to

the carriage for reciprocating movement over and in contact with the inside face of the grid.

4. In a shaving device of the character described, a casing having at least one flat face formed with an aperture, a normally plane flexible perforated grid resting on the edges of said aperture, a plurality of cutting edges uniformly distributed over most of the surface of the grid to press thereon, and a reciprocable cover on the casing for moving the cutting edges back and forth. 10

5. A dry shaver of the character described consisting of a flexible normally plane formaminous grid, a casing having an aperture and supporting said grid over the edges of the aperture, a member slidable in a plane parallel to that of the grid, and equally-spaced cutting knives mounted on the slidable member and adapted to reciprocate therewith in contact with the inside face of the grid. 15

6. As an article of manufacture, a dry shaver comprising a casing having an aperture in the bottom thereof, a flexible normally plane formaminous grid resting across the edges of the aperture, a carriage slidably mounted inside the cas- 20
